UNITED STATES PATENT OFFICE.

ROBERT W. WIEDERWAX, OF ATLANTIC CITY, NEW JERSEY, ASSIGNOR TO GEIST MANUFACTURING COMPANY, OF ATLANTIC CITY, NEW JERSEY, A CORPORATION OF DELAWARE.

HEATING DEVICE

Application filed January 28, 1922. Serial No. 532,508.

To all whom it may concern:

Be it known that I, ROBERT W. WIEDERWAX, a citizen of the United States, residing at Atlantic City, in the county of Atlantic and State of New Jersey, have invented certain new and useful Improvements in Heating Devices, of which the following is a specification.

This invention relates to heating devices for the cooling systems of motor vehicles.

In the present invention, I provide a casing adapted to fit the front and rear of a radiator having shutters to control the flow of air through the radiator. A burner is arranged within the casing at the front and a passage is provided for air to support combustion. The products of combustion pass off through a vertical passage communicating with a horizontal passage at the top of the casing which is arranged adjacent a portion of the air passage to preheat the air. Thence, the products of combustion pass through the radiator.

An object of the present invention is the provision of a heater comprising a casing which may be closed when the burner is lighted for heating purposes and opened when the vehicle is running.

A further object of the invention is the provision of means for supplying preheated air to the burner.

A further object is the provision of means for preheating the air by the products of combustion and then passing the products of combustion through the radiator.

In the accompanying drawings, I have shown one embodiment of the invention. In this showing:

Figure 1 is a front elevation of a motor vehicle showing the invention applied.

Figure 2 is a horizontal sectional view taken on line 2-2 of Figure 1.

Figure 3 is a detail view of a portion of the casing,

Figure 4 is a transverse vertical sectional view through the casing,

Figure 5 is a detail view of the burner removed,

Figure 6 is a vertical sectional view on line 6-6 of Figure 2,

Figure 7 is a side elevation of the casing,

Figure 8 is a central vertical sectional view on line 8-8 of Figure 1,

Figure 9 is a detail view of the shutter actuating mechanism,

Figures 10 is a horizontal sectional view on line 10-10 of Figure 8, and,

Figure 11 is a detail sectional view on line 11-11 of Figure 4.

Referring to the drawings, the reference numeral 1 designates generally a motor vehicle provided with a radiator 2. The radiator communicates with the lower water chamber 3, and an upper chamber 4, each of which is connected to the cooling jacket of the engine (not shown), in the usual manner.

The heater forming the subject matter of the present invention comprises a front casing 5 which is arranged in front of the radiator and supported in any suitable manner. As shown, the casing is provided with side walls 6, the ends of which are flanged, as at 7. A strip 8 is secured to the side wall adjacent the flange, and this strip is provided with a pair of flanges 9 and 10, arranged substantially parallel to and spaced from the flange 7.

The front wall adjacent the radiator is formed of alternate stationary and movable plates producing a shutter effect. As shown, the stationary plates 11 are secured between the flanges 9 and 10 by suitable fastening elements 12. The movable plates 13 are arranged between each pair of stationary plates, and the ends of these movable plates are offset, as at 14, and received between the flanges 7 and 9. These plates are arranged slightly off-set from the vertical plane of the stationary plates, as shown in Figure 2. The movable plates are connected to a rod 15, having a rack 16 formed adjacent its upper end. This rack meshes with a pinion 17, carried by a horizontal rod 18, extending through the radiator and provided with an operating handle 19 in front of the casing.

The rear of the radiator is closed by a casing or plate which is likewise provided with alternate stationary and movable sections. This rear plate consists of stationary sections 20 and movable sections 21. The movable sections 21 are provided with off-set ends 22, which are received in spaces formed by plates 23 and 24 of vertical strips 25, secured to the rear of the radiator. These movable sections are similarly connected by

a rod 26 having a rack formed thereon, meshing with a gear 27 carried by the horizontal shaft 18. As shown in Figure 8, of the drawings, the horizontal shaft may be 5 extended rearwardly to the dash of the vehicle (not shown) and provided with an operating handle 28. The movable front and rear strips adjacent the shaft 18 are provided with slots 29 to permit the plates to 10 move upwardly.

Beneath the bottom of the radiator, the front is provided with a solid wall 30 and a bottom 31. The wall 32 extends upwardly from the bottom of the front casing to the 15 lower level of the radiator. At the top of the radiator, the casing is provided with an inclined wall 33 having a plurality of openings 34. Beneath the inclined wall, there is provided an air passage 35, formed by 20 horizontal walls 36 and 37, and vertical walls 38 at the front and rear. This passage communicates with openings 34, by means of an inclined passage 39. Adjacent the side of the passage 35, there is provided an air duct 40, extending to a point beneath the upper end of the wall 32. At the opposite side of the casing, a vertical passage 41 is provided. This passage forms 25 a flue for the escape of products of combustion, and communicates with a space 42, at the top of the casing above the air passage 35. The walls of the air passage 35 may be provided with openings 42'.

Adjacent the bottom, there is provided a 30 horizontal wall 43, extending from one side of the casing to the vertical wall forming the inner side of passage 41. The end of the air duct 40 passes through this wall. The horizontal wall 43 and the bottom form a 35 burner casing which is adapted to receive a burner casing 44. The burner casing comprises a fuel tank 45, and a burner tank 46, separated from each other by a perforated wall 47. The fuel tank is provided with a 40 filling opening, closed by a cap 48. The burner tank is provided with a filling 49 of suitable fibrous material to retard the flow of liquid fuel. A burner 50 is arranged on the top of this tank, the burner comprising 45 a base plate having openings 51 for the passage of air spaced from the top of the burner tank by legs 52. A wick 53 is mounted in a wick chamber 54, and is provided with the usual control member 55. The bottom of 50 the wick extends through the top of the burner tank, as shown in Figure 4 of the drawings. When the burner is in position, the top of the burner co-operates with the horizontal wall 43 to form a transverse air 55 passage 56 to deliver air from the air duct 38 to the burner. The side wall adjacent the burner is provided with a door 57 hinged thereto, as at 58, which may be opened to insert and remove the burner and fuel tank. 60 This door is provided with a slot 59 for the

passage of the burner control member 55, and is further provided with a transparent window 60 to permit inspection of the flame. The door may also be provided with a suitable catch 61.

Beneath the radiator, the walls 30 and 32 of the front casing are provided with aligned openings in which a sleeve 62 is arranged. The starting crank 63 of the engine is adapted to be passed through this sleeve.

The operation of the device is as follows:

When the engine is running, or in warm weather, the shaft 18 is revolved through handle 19 or 28 to move the plates 13 and 21 upwardly behind the plates 11 and 20 and thus permit passage of air through the radiator for the purpose of cooling the fluid in the cooling system of the motor. When the engine is standing in cold weather and there is danger of freezing, the burner 50 is 25 lighted and the products of combustion pass up through the vertical chamber or flue 41 to the space 42. From the space 42, the gases pass around the tubes of the radiator, heating the water or other fluid and preventing 30 it from freezing. The flow of the products of combustion creates a draught in the horizontal passage 56, causing air to enter openings 34 and pass through passages 35 and 39 to the air duct 40. The incoming air in 35 the passage 35 is heated by the products of combustion in the space 42. It will be noted that this space is open in the front of the horizontal passage 35, which permits the 40 products of combustion to flow on all sides of the air passage 35 before passing through the radiator.

The openings 42' are provided to permit escape of some of the incoming air through the radiator when the amount of air supplied is more than is necessary to support combustion. The air passing through openings 42' joins the products of combustion and passes through the radiator. The products of combustion in the flue 41 heat the 45 space between the front wall of the front casing and the front of the radiator, and this heat is conveyed by radiation through the radiator, thus heating the entire radiator. The space 42 being in free communication with the radiator, except at one side where the flue 41 is provided, any back drafts escape downwardly into the space 50 between the casing and the front of the radiator and do not pass into the flue 41 and 55 interfere with the proper operation of the burner.

While I have shown the rear casing extending the entire height of the radiator, it is not always necessary to provide a closure 60 for the entire rear face of the radiator, and in some instances, the casing is terminated at a point above the vertical center of the radiator.

The depth or thickness of the burner and 65

- 5 tank are equal to the space between the walls 30 and 32 and the burner fits snugly within this space. When the burner is in the assembled position, the horizontal plate 50 forms a continuation of wall 43 and the air to support combustion passes upwardly through the openings 51. The burner can be readily removed and replaced by opening the door 57.
- 10 10 It is to be understood that the form of my invention herewith shown and described is to be taken as a preferred example of the same, and that various changes in the shape, size, and arrangement of parts may be resorted to without departing from the spirit of the invention or the scope of the subjoined claims.
- 15 Having thus described my invention, I claim:
- 20 1. A heater for automotive radiators comprising a casing adapted to be secured to the front of the radiator, said casing being provided with a horizontal air chamber, a burner arranged in the lower portion of said casing, means for delivering air from said horizontal air chamber to said burner, means for conveying the products of combustion from said burner, and a horizontal passage adapted to receive the products of combustion, said passage being arranged adjacent said horizontal air chamber.
- 25 2. A heater for automotive radiators comprising a rear plate adapted to be secured to the rear of the radiator, a front casing adapted to be secured to the front of the radiator, said casing being provided with a horizontal air chamber, a burner arranged in the lower portion of said casing, means for delivering air from said horizontal air chamber to said burner, and means for preheating the air to be supplied to said burner by the products of combustion from said burner.
- 30 3. A heater for automotive radiators comprising a casing adapted to be arranged in front of the radiator, said casing being provided with an air chamber adjacent the top, the wall of the casing being provided with openings to admit air to said chamber, a burner arranged in the bottom of said casing, an air duct to permit passage of air to said burner, and means for preheating the air by the products of combustion from the burner.
- 35 4. A heater for automotive radiators comprising a casing adapted to be arranged in front of the radiator, said casing being provided with an air chamber adjacent the top, the wall of the casing being provided with openings to admit air to said chamber, a burner arranged in the bottom of said casing, an air duct to permit passage of air to said burner, a vertical flue ar- ranged over said burner to convey the products of combustion upwardly, a horizontal passage arranged beneath said air chamber to preheat the incoming air by said products of combustion, and means for delivering the products of combustion through the radiator.
- 40 5. A heater for automotive radiators comprising a plate adapted to be arranged at the rear of the radiator, said plate being provided with openings, shutters adapted to close said openings, a casing arranged at the front of the radiator and provided with an open rear wall adjacent the radiator, the front of the casing being provided with a plurality of openings, shutters closing said openings, a burner arranged in the lower portion of said casing, means for delivering air to said burner, and means for preheating the air by the products of combustion from said burner.
- 45 6. A heater for automotive radiators comprising a plate adapted to be arranged at the rear of the radiator, said plate being provided with a plurality of openings, shutters adapted to close said openings, a casing adapted to be arranged in front of the radiator and extending below it, the rear wall of said casing adjacent the radiator being open, the front wall being provided with a plurality of openings adjacent the radiator, shutters adapted to close said openings, the lower portion of said casing being adapted to receive a burner, means for supplying air to said burner, and means for preheating said air by the products of combustion from said burner.
- 50 7. A heater for automotive radiators comprising a plate adapted to be arranged at the rear of the radiator, said plate being provided with a plurality of openings, means for closing said openings, a casing arranged in front of the radiator and extending below it, the rear wall of said casing being open adjacent the radiator, the front wall of said casing adjacent the radiator being provided with a plurality of openings, means for closing said openings, means for introducing air into the upper portion of said casing, a vertical air duct extending from the upper portion of the casing to the lower portion thereof, a burner arranged in the lower portion of said casing, a horizontal wall arranged in the lower portion of said casing to direct air to the burner, and means for preheating the incoming air by the products of combustion from said burner.
- 55 8. In testimony whereof I affix my signature in presence of two witnesses.
- 60 9. ROBERT W. WIEDERWAX.
- 65 10. Witnesses:
- 66 11. THEODORE W. WARRINGTON,
67 12. MORTON COLLINS.
